UNITED STATES PATENT OFFICE.

JOHN HAYS HAMMOND, JR., OF GLOUCESTER, MASSACHUSETTS.

MULTIPLEX RADIOTELEPHONY.

1,372,426.

Specification of Letters Patent. Patented Mar. 22, 1921.

Application filed May 29, 1912, Serial No. 700,426. Renewed March 15, 1919. Serial No. 282,960.

To all whom it may concern:

Be it known that I, JOHN HAYS HAMMOND, Jr., a citizen of the United States, residing at Gloucester, in the State of Massachusetts, have invented certain new and useful Improvements in Multiplex Radiotelephony, of which the following is a specification.

My invention relates to systems for transmitting and receiving two or more telephone conversations simultaneously by means of electric waves, and relates more particularly to such systems where electric waves having different lengths are employed for this simultaneous, or multiplex, telephony. Heretofore two oscillation generators have been used at the transmitting station, each generating electric waves of a definite length, but by my invention it is possible to use only one generator for generating any required number of sets of electric waves, the waves in each set having different lengths from those in the other sets. This will be shown more fully by the following description, reference being had to the accompanying drawings.

Figure 1 shows a transmitting station on my system of multiplex radio telephony.

Fig. 2 shows a corresponding receiving station on my system.

In Fig. 1, an oscillatory arc O is supplied from a source of direct current M N. Shunted around O are two oscillating circuits O L C and O L¹ C¹, containing the inductance coils L and L¹, and the condensers C and C¹, respectively, which are in resonance with the antenna circuits A L² T E and A L³ T¹ E, respectively, to which they are respectively coupled through the coils L² and L³. It is well known that an electric arc of the type shown comprises two electrodes, one of which, the cathode, is always negative, and emits electrons when in operation. The arc O constitutes a thermionic oscillator. The antenna A is grounded at E, and as the circuits O L C and O L¹ C¹ have different oscillation periods, the antenna A will radiate continuous undamped waves of two lengths. The telephone transmitters T and T¹, when under the influence of sound waves, will produce amplitude variations in the currents in the respective antenna circuits, and hence like variations in the electric waves radiated from the antenna A.

In Fig. 2, B is an antenna grounded at

E¹, and having two circuits B L⁴ C² E¹ and B L⁵ C³ E¹, these circuits containing the inductance coils, L⁴ and L⁵, and the condensers, C² and C³, respectively, and being coupled to the closed oscillation circuits L⁶ C⁴ and L⁷ C⁵ through the coils L⁵ and L⁷, respectively. The antenna circuit B L⁴ C² E¹ and the oscillation circuit L⁶ C⁴ are in resonance with each other and with one of the wave frequencies of the transmitting station, and the antenna circuit B L⁵ C³ E¹ and the oscillation circuit L⁷ C⁵ are in resonance with each other and with the other wave frequency of the transmitting station.

When the circuit L⁵ C⁴ is energized by the electric waves in resonance with it, the rectifier R will deliver unidirectional current corresponding to the current variations caused by the transmitter T, in Fig. 1, to the telephone receiver P, where the sounds produced at T will be reproduced. In like manner when the circuit L⁷ C⁵ is energized, the rectifier R¹ will deliver unidirectional current to the telephone P¹ which will thus reproduce sounds produced at T¹, in Fig. 1.

Although in the particular embodiment of my invention here shown there are only two sets of circuits, and only two telephone conversations can be carried on simultaneously, my invention is not limited to two sets of circuits, but may employ three or more sets of circuits, so that three or more telephone conversations can be carried on simultaneously. Instead of telephone apparatus I can employ telegraph apparatus at both transmitting and receiving stations, for the simultaneous transmission and reception of two or more telegraph messages, or I can use both telephone and telegraph apparatus at both transmitting and receiving stations, and transmit and receive telephone conversations and telegraph messages simultaneously. And, moreover, I do not confine myself to the particular apparatus or circuits here shown, but may employ any other apparatus or arrangement of circuits suitable for my purpose.

I claim as my invention:

1. In a system of multiplex radio telephony, a plurality of oscillation circuits connected with a single arc, said oscillation circuits having different periodicities, secondary circuit coupled to each of said oscillation circuits and connected to a single antenna, a telephone transmitter in operative

- relation to each of said secondary circuits, and a receiving station comprising a plurality of circuits tuned to the different wave lengths emitted by the transmitting station.
- 5 2. A system of multiplex radio telephony having a transmitting station comprising a single arc connected with a source of energy, a plurality of circuits in parallel connection with said arc, each of said circuits having different electrical constants, an antenna having branches containing inductance coils, each of said branches being coupled with one of said oscillating circuits, and a telephone transmitter operatively associated with each of said branches, and a receiving station comprising a plurality of circuits tuned to the wave lengths of the transmitting station, and operatively connected with telephone receiving apparatus.
- 10 3. In a system of electric wave transmission, a plurality of oscillation circuits connected with a single arc, said oscillation circuits having different periodicities, secondary circuits coupled to each of said oscillation circuits and connected to a single antenna, and a receiving station comprising a plurality of circuits tuned to the different wave lengths emitted by the transmitting station.
- 15 4. In a system of multiplex radio telephony, the combination with a source of elec- troradiant oscillations, of means for simultaneously impressing a plurality of series of undulations corresponding to sound waves upon the said oscillations, and receiving means including a plurality of devices selectively responsive respectively to said plurality of series.
- 20 5. A transmission system for multiplex radio signaling, comprising a transmission circuit, a plurality of secondary circuits connected to said transmission circuit, an electric arc, a source of electric energy connected to said arc for energizing the same, and a plurality of oscillation circuits tuned to different frequencies respectively and respectively coupled to said secondary circuits and shunted around said arc.
- 25 6. A transmission system for multiplex radio signaling, comprising a transmission circuit, a plurality of secondary circuits connected to said transmission circuit, an electric arc, a source of electric energy connected to said arc for energizing the same, a plurality of oscillation circuits tuned to different frequencies respectively and respectively coupled to said secondary circuits and shunted around said arc, and a signaling device arranged to act upon each of said secondary circuits.
- 30 7. A multiplex system comprising a single arc, a plurality of oscillation circuits tuned to different frequencies respectively and connected to said arc, a single antenna operatively connected to said circuits and a signaling device arranged to control each of said oscillation circuits whereby a plurality of messages may be simultaneously transmitted through said antenna.
- 35 8. A multiplex system comprising a single arc, a plurality of oscillation circuits tuned to different frequencies respectively and connected to said arc, a single conductor operatively connected to said circuits and a signaling device arranged to control each of said oscillation circuits whereby a plurality of messages may be simultaneously transmitted through said conductor.
- 40 9. In a system of multiplex signaling, a thermionic oscillator, a plurality of circuits associated therewith and arranged to have simultaneously produced therein respectively as a result of the action of said oscillator, a plurality of series of periodic electrical impulses of different frequencies respectively, and a plurality of signaling devices associated with said circuits respectively whereby a plurality of different messages may be simultaneously generated.
- 45 10. In a system of multiplex signaling, an oscillator having an electron emitting cathode, a plurality of circuits associated with said oscillator and arranged to have simultaneously generated therein respectively, as the result of the action of the oscillator, a plurality of series of periodic electrical impulses having different frequencies respectively, and a plurality of signaling devices associated with said circuits respectively whereby a plurality of different messages may be simultaneously generated.
- 50 11. In a multiplex system of signaling, the combination with an oscillator, of a plurality of circuits associated therewith and arranged to have simultaneously produced therein respectively as a result of the action of said oscillator, a plurality of series of periodic electrical impulses having different frequencies respectively, one of said frequencies being substantially outside of the range of audibility, and a plurality of signaling devices associated with said circuits respectively whereby a plurality of different messages may be simultaneously generated, one of said signaling devices associated with the circuit having generated therein a frequency substantially outside of the range of audibility, being a telephone transmitter.
- 55 12. A multiplex transmission system comprising a thermionic oscillator, a plurality of circuits associated with said oscillator and arranged to have generated therein respectively as a result of the action of said oscillator a plurality of series of periodic electrical impulses of different frequencies respectively, and a plurality of signaling devices associated with said circuits respectively whereby a plurality of different messages may be simultaneously transmitted.

13. A multiplex transmission system comprising a thermionic oscillator, a plurality of circuits associated therewith and arranged to have generated therein respectively as a result of the action of said oscillator, a plurality of substantially ultra-audible periodic electrical impulses of different frequencies respectively, and a plurality of separately operated signaling devices associated with said circuits respectively whereby a plurality of different messages may be simultaneously transmitted.

14. In a system of multiplex radiotelephony, a sending station comprising telephone transmitting apparatus; a plurality of oscillation circuits connected with a single arc, said oscillation circuits generating a plurality of series of electric waves of different frequencies respectively, each of said 20 series of waves having amplitude variations

impressed thereon by said telephone transmitting apparatus, and a receiving station comprising a plurality of circuits tuned respectively to said frequencies.

15. In a system of multiplex radio telephony, the combination with a source of electronradiantr oscillations, of means for simultaneously impressing a plurality of series of undulations corresponding to sound waves upon the said oscillations, and receiving means including a plurality of devices selectively responsive respectively to said plurality of series. 25 30

This specification signed and witnessed this 22nd day of May A. D., 1912.
